UNITED STATES PATENT OFFICE

JOHN M. YOUNG, OF BROOKLYN, NEW YORK, ASSIGNOR TO AMERICAN CAN COMPANY, OF NEW YORK, N. Y., A CORPORATION OF NEW JERSEY

APPARATUS FOR VACUUMIZING AND GASSING CANS

Application filed December 31, 1924. Serial No. 759,192.

This invention relates to apparatus for removing air from filled containers and substituting therefor an inert preserving gas.

A method commonly employed for vacuumizing and gassing food containers consists in placing the container within an air-tight bell, or chamber, establishing communication between said bell or chamber and a vacuum pump, or the like, to exhaust the desired amount of air, which is thereafter replaced by the introduction of the preserving gas into the vacuumized space within the container.

The apparatus used for this purpose in the past has depended upon the pressure of the surrounding atmosphere acting upon the vacuum bell after a rarefied air condition has been created in the chamber to hold said bell firmly upon its seat and to establish a seal between the outside atmosphere and the space within the chamber. As the gas is introduced into the chamber, however, the difference in pressure is lessened, so that the seal becomes less effective and may be broken if no other sealing means than the outside atmospheric pressure be employed.

It is an important object of my invention, therefore, to provide, for the purpose stated, simple and efficient mechanical means for holding the vacuum bell down upon its seat, thereby rendering it unnecessary to depend upon atmospheric pressure solely to maintain a proper seal between the interior and exterior of the bell chamber.

Another object of the invention is the provision of an easily controllable and quickly operable device, of improved construction, for quickly and efficiently performing the operations involved in the process described.

Numerous other objects and advantages of the invention will be apparent as it is better understood from the following description, which, taken in connection with the accompanying drawings, discloses a preferred embodiment thereof.

Referring to the drawings,

Figure 1 is a perspective view of an apparatus embodying my invention;

Fig. 2 is a front-to-back vertical sectional view thereof, certain of the parts being shown in section and a container being positioned

within the vacuum bell, which is shown held down in fixed position; and

Fig. 3 is a sectional and plan view, taken substantially upon the section line 3-3 in Fig. 2 and illustrating the air and gas valves and control therefor.

As thus illustrated, the machine comprises a table 11, supported upon legs 12 arising from a base 13, said table 11 being formed to support the container to be gassed and the various parts of the mechanism employed in the process. A countersunk seat 14 is provided in the top of the table for the container 15, which may be positioned by hand, or by any suitable feeding mechanism, it being understood that said container has been previously filled and, in accordance with usual practice, has one end open, the cover or upper end being subsequently applied. Inasmuch as the gas is heavier than the atmosphere, it will not be lost within the period of time necessary to transfer and close the can.

Surrounding the seat 14 is a ring, or washer, 16, which is positioned in an annular groove 17 and is formed of rubber, or like resilient material, the upper surface of said ring being flush with the top of the table. A bell 18 is provided to close down over the container and provide an enclosed space from which the air may be withdrawn and into which the gas may be introduced in accordance with the process for which the apparatus of my invention is provided. Said bell has a rearward extension 19, which is hinged by means of a pin 21 to spaced upright lugs 22, formed upon the rear edge of the table 11. A counterweight 23 is secured to the rear of the extension 19 by means of a threaded rod 24 and is adapted to facilitate movement of the bell 18 about the pivot pin 21.

A gauge 25 is provided upon the top of the bell for the purpose of indicating the pressure within the chamber.

An operating handle 26 is pivoted at 27 to outstanding lugs 28 upon the front of the bell 29 and is provided with a downwardly extending hook 29, adapted to engage a catch 31 extending upwardly above the table 11 at the front thereof. Said catch is slidably mounted in an opening 32 in the table and has a rod por-

tion 33 extending downwardly beneath the table and threaded at its lower end, as indicated at 34, and carrying an adjusting nut 35 and a lock nut 36, a coil spring 37 surrounding said rod and being compressed between the under side of the table and the adjusting nut 35, which latter obviously may be manipulated to vary the tension upon said spring. Cooperating shoulders 38 and 39 are formed, respectively, upon the table and the catch 31, to limit the downward movement of the latter.

After the can has been positioned, the operator may lower the bell 18 by means of the handle 26, said bell having a channel 41 formed in the bottom edge thereof and said edge being adapted to tightly engage and slightly imbed itself in the annular gasket 16. As the handle is moved downwardly, the hook 29 thereon is caused to engage the catch 31, which is slightly lifted against the tension of the spring 37, thus holding the bell down tightly against its seat and maintaining a proper seal at all times between the interior and exterior thereof. A spring 42 has its opposite ends disposed in recesses 43 and 44 provided, respectively, in an upwardly extending lug 45 on the handle and the front of the bell.

After the bell is closed down and locked in the position shown in Fig. 2, communication may be established between the interior of said bell and a vacuum source, such as a vacuum pump, or tank, which has not been shown in the drawings. This is accomplished by manipulation of a control lever or handle 46, which is pivoted upon a stud 47, depending from the lower surface of the table 11. Said lever is provided with a raised boss 48, adapted to engage a stem 49 of a valve 51, which is connected by means of an elbow 52 with a pipe 53 leading to the vacuum source, the opposite side of said valve communicating through a tubular extension 54 and an opening 55 in the table with the interior of said bell. The tubular extension 54 is threaded into the under side of the table and the valve thus supported. After sufficient air has been exhausted, as indicated by the gauge 25, the lever 46 is turned upon its pivot to permit the valve, which may be of well known self-closing construction, to close and a head 56 upon an extension 57 of said lever is brought into contact with a stem 58 of a valve 59 which controls the admission of gas delivered through a pipe 61 from any suitable source, said valve 59 being similar in construction to the valve 51 and having a corresponding tubular extension 62 threaded into the under side of the table. A tube 63 is threaded into an opening 64 in the table at this side and extends upwardly to adjacent the top of the can, so that the gas may be delivered above the open mouth of the container and, due to

its tendency to settle, will thoroughly fill the vacuumized space within said container. This gas may be any suitable inert preserving gas, such, for example, as carbon dioxid. After a sufficient amount of gas has been admitted, the lever 46 may be turned to neutral position, which releases the stem 58 of the valve 59, permitting said valve to automatically close, the lever at this time being in contact with both valve stems, but not depressing them sufficiently to establish communication either with the source of vacuum or the gas supply.

By means of the described apparatus, I am enabled to exhaust the air from a filled container and substitute therefor a preserving gas very rapidly and with semi-automatic action, the device being at all times under accurate control of the operator and being adapted for long continued, efficient performance under ordinary conditions of use.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. Apparatus for vacuumizing and gassing filled cans, comprising a support for the can, an enclosing member rotating around a pivotal point and movable down over said can, a seat upon which said member is adapted to rest to seal the interior thereof against the outside atmosphere, interengageable parts associated respectively with said member and said seat and adapted to positively hold the same in sealing engagement, said parts being engageable in the normal closing action of said member and a spring placing said enclosing member under spring tension, and a vacuum pipe for withdrawing the air and means for introducing the gas into the can.

2. Apparatus for vacuumizing and gassing filled containers, comprising a table, a vacuum bell pivotally connected with said table and movable down over a can supported on said table, a weight for balancing said bell, means including a valve for withdrawing air from the can, means including a valve for introducing gas into said can, and a single control for both said valves, said control being adapted to hold one valve closed when the other is open and having a neutral position with both valves closed.

3. Apparatus for vacuumizing and gassing filled containers, comprising a table, a vacuum bell movable down over a can supported on said table to enclose the can and

space about the can, a pipe for withdrawing air from the bottom of said space, and a pipe extending up from the table and within the bell for introducing gas at a substantial height in the space adjacent the open upper end of the can.
